GAS-FIRED WATER HEATER

Walter Brümmerhoff, Remscheid-Lenne, Germany, assignor to Johann Vaillant Kommanditgesellschaft, Remscheid, Germany

Application October 4, 1951, Serial No. 256,036

7 Claims. (Cl. 122—451.2)

This invention relates to gas-fired boiling-water heaters and, more particularly it has reference to water heaters employing the continuous flow principle for heating cold tapping water to boiling temperature, as distinguished from hot-water heaters delivering hot but no boiling water.

Ordinary gas-water heaters for delivering boiling water heretofore in use have been of the open, pressureless type which are attended by the detrimental feature of generating a great deal of steam and requiring a relatively long starting up period till boiling water can be withdrawn therefrom.

The invention is based on the discovery that it is possible, under certain suppositions, to use the closed construction usually employed for hot-water heaters, also to advantage for boiling-water heaters instead of the open, pressureless construction. The term closed construction applies in the present case to such a one in which the water is heated by the continuous flow system which is in heat-exchange with a heating chamber flue. The continuous flow system can be formed, in a known manner, as simple pipe coil. If, however, water is brought to boiling temperature in such a continuous flow system, the steam, forming in the small-diameter pipes or tubes, disturbs the flow of water and causes increased incrustation.

The invention consists in preventing prejudicial boiling of the water in the closed, continuous flow system by providing a spring-loaded pressure relief valve on the service-end thereof. This will cause that, depending upon the tension of the spring, a pressure above atmospheric is built up in the continuous flow system, which pressure notwithstanding the heating of the water to normal boiling temperature prevents its boiling in the coil. Hence, the water does not boil until it is relieved of the pressure after its discharge from the heater. This pressure is so adjusted that boiling water can still be drawn also under unfavorable service conditions of gas and water, yet preventing boiling of the water in the pipe coil.

Unobjectionable, i. e., trouble-free operation of such a water heater depends chiefly upon suitable construction of the pressure relief valve. The relief valve must act in such a manner that a certain quantity of water, which is requisite for obtaining water of boiling temperature on the service-end of the heater, can flow out of the continuous flow system at and above a certain pressure only. As long as this pressure is not extant the relief valve must be kept in closed position, so that the heater, owing to the reaction of the so-called water deficiency safety device (which automatically shuts off the gas if there is not enough water flowing through the system) will not be put in operation. Yet, upon a slight exceeding of the required pressure, the relief valve must respond at once and release a large passage area, so as to prevent shattering of the valve body, and also for such reasons as to prevent that there is no substantially higher pressure extant in the heater than that required for boiling water delivery if the heater is operated as hot-water heater. Further re-

quirements are that the relief valve is not susceptible to (or protected against) incrustation of the valve seat.

It is therefore an object of the invention to provide in a continuous-flow water heater a relief valve which will fulfill these requirements and which is otherwise well adapted for the purpose for which the same is intended.

It is known that an after-heating of the fluid takes place, which is still within the pipe coil, when any continuous flow heater is shut off, because the fluid takes up the heat which is yet stored in the heat-exchanger. This after-heating, which means a heat loss which should not be disregarded, is of great disadvantage particularly in boiling-water heaters, which according to the invention operate by the continuous flow principle, because the after-heated water, resting in the coil, will be the cause of an increase in incrustation.

It is therefore an important object of the invention to overcome these disadvantages of such after-heating by providing a tapping valve of special form, which is particularly suitable for the end in view. Namely, the valve is so formed that, in the course of closing—shortly before it is fully closed—a transitory increase in passage area takes place. Consequently, the hot water, still in the coil after the water deficiency safety device has been shut off, will be pushed out of the heater, shortly before the valve is fully closed, by an additional quantity of water which is fed into the coil, so that, after the water has been shut off completely, the water remaining in the heater at first is almost cold, and it is not brought any more to the critical temperature at which the precipitation of scale begins by this after-heating.

These and other objects and advantages of the invention will more fully appear from the following description made in connection with the accompanying drawings in which one embodiment of the invention is illustrated diagrammatically by way of example.

In said drawings:

Fig. 1 illustrates the boiling-water heater according to the invention in partially sectioned elevation, showing the essential parts of the invention on a larger scale,

Fig. 1a is a plan of the finned heating element, and

Fig. 2 illustrates another form of the tapping valve in side sectional elevation.

Disposed above a gas burner 1 is a flue 2 which is closed at the top by means of a finned heating element 3. A water-carrying pipe coil 4 is wound around the outside wall of the flue 2 several times and also passes through the finned heating element 3 several times.

The starting end of the coil 4 is connected to the housing 5 of a hand operated tapping device 6. Supported in the valve housing 5 is a valve spindle 7 by means of which a valve member 8 can be set as to the valve seat 9. Another valve member 10, which is provided with a spacing pin 10', is urged into abutting engagement with the valve spindle 7 by means of a spring 11. When the valve 8 is open, the auxiliary valve member 10 is spring-urged upon its seat 12. The cold-water supply pipe 13' is connected to the pipe connection 13 on the valve housing 5. A duct 14 communicates upstream of the auxiliary valve 10, 12 with the cold water supply pipe 13, whereas another water duct 15 establishes communication between a point between the valve seats 9 and 12 and the supply pipe 13. A throttle member 17, which is under the compression of a spring 16, is disposed within the water duct 15 and, by its position, determines the quantity of water flowing through the duct.

A throttle member or flow restrictor 18 is mounted within the starting-end of the pipe coil 4. A pipe 19, leading to the chamber 20 of a diaphragm casing 21, branches off upstream of the throttle member 18. The lower diaphragm chamber 20 is separated by means of a rubber diaphragm from the upper diaphragm chamber

23, which is in communication with the coil 4 by means of a pipe 24 connected to the coil downstream of the throttle member or flow restrictor 18. The diaphragm 22 controls a gas valve 26, disposed in the gas supply pipe 25 for the burner 1, in a known manner as water deficiency safety device.

The service-end of the coil 4 is connected to the housing 27 of a relief valve. There is a projecting valve seat on the bottom of the housing upon which the valve head 29 is seated. The valve head 29 is by means of a screw 30 connected to a metal diaphragm 31 which closes the valve chamber. The diaphragm 31 is stressed downwardly by a compression spring 32 which on its one end is seated upon a shoulder on the screw 30 and on its other end upon the cap 34 having a vent hole 33. The head of the screw 30 can abut the cap 34 and thereby limit the travel of the diaphragm 31 in such a manner that the diaphragm 31 can unseat the valve head 29 a sufficiently great distance from its seat.

The principle of operation of the described boiling-water heater is the following: when the tapping valve 6 is open the cold water flows through the duct 15 via the valve 8 to the coil 4. The throttle member 17 permits only a certain quantity of water to pass through which is determined by the compression of the spring 16. If, due to increased pressure, cold water flow is increased more than desired, the throttle member is raised accordingly thereby reducing the passage area. The throttle member 17 in conjunction with the spring 16 acts therefore as simple water-quantity regulator.

As soon as a certain quantity of water flows a pressure difference is formed across the throttle member 18 and consequently also in the diaphragm chambers 20, 23, and the gas valve 26 is opened and kept open by means of this pressure difference. However, the water can only flow and in turn actuate the water deficiency safety device if there is a water pressure which is great enough to open the relief valve 28, 29 on the discharge end.

The water flowing through the coil 4 is, during its passage therethrough, heated to atmospheric boiling temperature by the gas burned in the burner 1. However, it does not boil and no steam is formed yet because it is kept in the closed coil 4 under pressure above atmospheric by means of the valve 28, 29. The water does boil and vaporize only after it has passed the relief valve 28, 29 and flows off.

The pressure acts upon the metal diaphragm 31, then overcomes the compression of the spring 32 and opens the valve 28, 29. After the valve 28, 29 has been opened, the effective area of pressure on diaphragm 31 is increased by an area of approximately the cross-sectional area of the valve opening 28, so that a lesser pressure is required to keep the valve open than that for opening it. Consequently, the valve 28, 29 once it is open cannot immediately be closed again when there is an insignificant reduction in pressure, so that chattering of the valve 29 cannot occur. In order to make the increase in effective area of pressure sufficiently large for all instances, the perimeter of the valve seat 28 is proportioned relatively large as compared with the free passage area so that the valve head 29 is seated upon a relatively wide valve seat.

As the hand operated tapping device 6 is closed the water passage between seat 9 and valve head 8 is continually decreased. But before the flow of water is shut off between 8, 9, the valve spindle 7 lifts the auxiliary valve from its seat 12, so that in this intermediate position an additional quantity of water can flow in through the duct 14 by bypassing of the duct 15. The hot water yet remaining in the coil 4 is pushed out by this additional quantity of water, so that at the precise moment as the water supply is shut off completely—hence when the water deficiency safety device 26 is actuated in the sense of closing—the coil 4 is filled only with water which is almost cold. The heat stored in the finned heating ele-

5
ment 3 and flue 2 is now transferred to the cold water. However, by this afterheating, the water is not brought anymore to the critical temperature in which precipitation of scale or incrustation begins.

Instead of the hand operated tapping device 6 there might be one installed having the form as shown in Fig. 2. In this valve provision is made for a relieved valve seat 36 in the valve housing 35 upon which a valve head 38 can be seated by means of a valve spindle 37. The valve head 38 is provided with a throttle member 40 having a contracted neck 39. The position of valve head 38 and throttle member 40 in open position of the valve is indicated by dotted lines. As this tapping valve is closed, the throttle member 40, first of all, enters the valve seat 36 and shuts the water supply almost completely off, so that the water deficiency safety device 26 is actuated in the sense of closing. But as soon as, upon further closing of the tapping valve, the throttle member 40 has passed through the valve seat 36 and the contracted neck 39 is within the valve seat 36, the quantity of water flowing through is transitorily increased, so that a certain quantity of cold water flows again into the coil 4, after the burner 1 is shut off, and takes up the after-heat. During this brief subsequent inflow of cold water, the water deficiency safety device 26, due to its inertia, is not actuated. Not till then the tapping valve is completely shut off by means of seating the valve head 38 upon the valve seat 36.

What is claimed is:

30 1. A gas heated continuous flow heater consisting of a gas burner, a flue for taking up the heating gases arranged above said burner, a closed pipe system, a cold-water supply pipe connected to said closed pipe system, means for transferring heat of said gas burner to said closed pipe system, a hand operated valve for controlling the quantity of water flowing through said closed pipe system, and means for transitorily increasing the passage area of said hand-operated valve during its closing movement before it is fully closed.

40 2. A gas heated continuous flow heater, consisting of a gas burner, a flue for taking up the heating gases arranged above said burner, a closed pipe system, a cold-water supply pipe connected to said closed pipe system, means for transferring heat of said gas burner to said closed pipe system, a hand operated tapping device for controlling the quantity of water flowing through said closed pipe system, said tapping device having a main valve and an auxiliary valve and means for operating both valves simultaneously, a main water duct controlled by said main valve and a by-pass arranged in parallel to said main water duct, said auxiliary valve being opened by said main valve and opening said by-pass before said main valve closes said main water duct.

55 3. A gas heated continuous flow heater, consisting of a gas burner, a flue for taking up the heating gases arranged above said burner, a closed pipe system, a cold-water supply pipe connected to said closed pipe system, means for transferring heat of said gas burner to said closed pipe system, a hand operated tapping device for controlling the quantity of water flowing through said closed pipe system, said tapping device having a main valve and an auxiliary valve and means for operating both valves simultaneously, a main water duct controlled by said main valve, a throttling device in said main water duct for setting the main quantity of water, and a by-pass arranged in parallel to said main water duct, said auxiliary valve being opened by said main valve and opening said bypass before said main valve closes said main water duct.

60 4. A gas heated water heater according to claim 6, said tapping valve having a main valve and an auxiliary valve and means for operating both valves simultaneously, a main water duct controlled by said main valve and a by-pass arranged in parallel to said main water duct, said auxiliary valve being opened by said main valve and

opening said by-pass before said main valve closes said main water duct.

5. A gas heated continuous flow heater consisting of a gas burner, a flue for taking up the heating gases arranged above the burner, a closed pipe system, a cold water supply pipe, connected to said closed pipe system, means for transferring heat of the burner to said closed pipe system, a valve member for controlling the quantity of water flowing through said closed pipe system, said valve member being axially movable by means of a spindle, an annular valve seat for said valve member, a throttle member provided with a contracted neck fastened to said valve member and said throttle member passing through said valve seat during the closing movement of said valve member.

6. A gas heated water heater consisting of a gas burner; a flue for taking up the heating gases arranged above said burner; a closed pipe system; a cold water supply connected to said closed pipe system; means for transferring heat of said gas burner to said closed pipe system; a hand operated tapping device at the feed intake of the closed pipe system for controlling the quantity of water flowing through said pipe system; a valve housing connected to the discharge end of said closed pipe system; a spring loaded diaphragm arranged in said valve housing; an outlet in said valve housing; and a valve body secured to said diaphragm in such a manner that the temperature of the water reaches the atmosphere boiling point without vaporization and which opens said outlet when a certain pressure in the closed pipe system is exceeded.

7. A gas heated water heater consisting of a gas burner;
